UNITED STATES PATENT OFFICE.

NAPOLEON HENRY SEYMOUR, OF WALTHAM, MASSACHUSETTS.

PLATING HALF-ROTARY FEED GUIDE.

Application filed May 4, 1922. Serial No. 553,486.

To all whom it may concern:

Be it known that I, NAPOLEON H. SEYMOUR, a citizen of the United States, residing at Waltham, in the county of Middlesex and State of Massachusetts, have invented certain new and useful Improvements in Plating Half-Rotary Feed Guides; and I do declare the following to be a full, clear, and exact description of the invention, such as will enable others skilled in the art to which it appertains to make and use the same.

This invention relates to an attachment for knitting machine and is known as a plating half rotary feed guide.

One object of the invention is to provide a device of the character described which may be connected with knitting machines of a conventional construction for knitting flat work thus permitting the attachment to be applied to machines already in use instead of guides already provided.

Another object of the invention is to so construct this guide that the thread carrying and guiding portion thereof may be turned at the end of each row of knitting before the return movement is started.

Another object of the invention is to so construct this attachment that the hollow thread carrying stem may be rotatably mounted and at the same time permitted of being slid vertically out of an operative position when so desired, spring means being provided to normally retain the thread carrying and guiding stem in an operative position.

Another object of the invention is to provide improved means for limiting rotation of this stem, this means for limiting rotation being clamped to the stem and extending in opposite directions beyond the stem.

Another object of the invention is to provide an improved bracket having abutment means for engaging a lever arm and swinging the lever arm to impart rotary movement to the stem.

Another object of the invention is to so construct this means for turning the lever arm that the arm-engaging plunger or rod may be yieldably held in a normal position and thus permitted to move under pressure and prevent breakage.

This invention is illustrated in the accompanying drawings, wherein:

Figure 1 is a perspective view showing the attachment applied to a conventional structure of knitting machine.

Figure 2 is an enlarged view showing the attachment in side elevation, portions of the knitting machine being shown in section.

Figure 3 is a view showing the attachment in elevation looking from the left of Fig. 2.

Figure 4 is a sectional view through the lower end portion of the stem taken along the line 4—4 of Fig. 3.

Figure 5 is a top plan view of the attachment.

Figure 6 is a sectional view taken along the line 6—6 of Fig. 2.

Figure 7 is a view showing the attachment in vertical section.

Figure 8 is a sectional view taken along the line 8—8 of Fig. 2.

Figure 9 is a view similar to Fig. 8 showing the yarn carrying and guiding stem turned for a half revolution.

This improved attachment is to be used in connection with a conventional construction of knitting machine which is indicated in general by the letter M and is not described in detail as it is to be understood that this is only one specific type of knitting machine with which the attachment can be used. This machine includes a bar B and a carriage C which moves longitudinally of the knitting machine. The attachment is to be carried by this movable carriage C and the yarns Y pass through the hollow stem of the device so that the yarn or thread will be properly guided to the needle of the knitting machine. One thread will be of a good quality and the second will be a cheaper grade of thread and when knit in the usual manner, the good thread and cheaper thread will be placed one on top the other, with the good thread showing upon the outer face of the material knitted and the cheaper thread showing upon the inner face.

Other devices are now in use for guiding the two threads of yarn so that a plated yarn formed of threads of different quality may be formed but they are not as strong and durable as this device or as efficient in operation.

This attachment is provided with a bracket 1 having a lower arm 2 which is bolted to the carriage C by means of the bolts 3. The bracket will therefore be securely held in place as shown clearly in Fig. 2 but may be removed when so desired, and cleaned or repaired and then replaced. This bracket 110 has its upper end provided with a head strip 4 which is provided with a socket 5 at

one end having a threaded opening formed therein so that the lever 6 may be pivotally mounted by means of a pivot screw 7 which extends through the bearing 8 of this lever 5 and has its lower threaded end portion screwed into the socket 5. The upper and lower arms 9 and 10 of the bracket 1 terminate in bearing sleeves 11 and 12 which receive and slidably and rotatably mount the 10 thread-guiding stem 13. This stem 13 is hollow for the greater portion of its length and as shown clearly in Fig. 7, the hollow passage 14 which forms a thread passage extends from the upper end of this stem to a 15 point beneath the lower bearing 12. The lower portion of this stem is cut from one side to provide a reduced neck portion 13' which is shaped in cross section as shown in Fig. 4 and at its lower end carries a head 20 15 having longitudinally extending openings 16 formed therein and leading from its upper end to one side of the neck 13' to its lower end. Therefore, the yarn can be passed through the yarn passage 14 and along 25 the flattened face of the neck 13' and then passed through the openings 16, the good grade of yarn being passed through one of these openings and the cheaper yarn being passed through the second opening. By having 30 the stem provided with the neck 13', the threads after being passed through the passage 14 can be very easily threaded through the openings 16 in the head 15. The upper end portion of this stem 13 is threaded 35 and carries a collar 17 which is screwed upon the upper end portion of this stem to the desired point and then anchored by means of a set-screw. A washer 18 is provided beneath this collar 17 to engage the face of the 40 upper bearing 11 and thus prevent wearing of the collar. Above the collar 17, there is provided a gear 19 which is screwed into place and anchored by means of a set-screw which passes through the reduced upper portion 19' of this gear or pinion. This gear 45 or pinion meshes with a rack 20 provided at the end of the operating handle or lever 6 and it will be readily seen that when the lever is swung upon its pivot 7, rotary movement will be imparted to the stem 13.

When this stem 13 receives rotary movement, it is only desired to have it rotate for approximately one-half of a revolution. Therefore, there has been provided an abutment yoke or bar 21. This yoke or bar 21 is positioned to extend transversely of the stem above the lower bearing 12 and upon the opposite side of the stem, there has been provided a clamping bar 22. These bars 21 and 22 are seated in notches formed in opposed sides of the stem and clamping screws 23 are passed through openings formed in the clamping bar 22 and screwed into openings formed in the yoke bar 21. From an inspection of Fig. 8, it will be readily seen

that when the securing screws 23 are tightened, the yoke bar will be firmly held in place and cannot have movement longitudinally of the stem or circumferentially thereof. This yoke bar extends from the stem as 70 shown and has its end portions offset and provided with threaded openings so that abutment pins 24 may be passed through the threaded openings of the yoke bar. By comparing Fig. 8 with Fig. 9, it will be 75 readily seen that the stem is free to rotate for approximately a one-half revolution, rotation being stopped by engagement of the abutment screws 24 with the sides of the bracket. It will be further noted that if it 80 is found that with the yoke bar set as shown, the stem turns a little more than desired or not quite enough, the abutment pins or screws 24 can be adjusted and then locked in the proper place by the lock nuts 24'.

It is sometimes desirable to permit the stem to be moved upwardly out of the way and therefore this stem may be moved upwardly through the bearings 11 and 12. It is of course however desired to have the stem 85 normally remain in the lowered or operative position with its pinion meshing with the pinion of the rack 20. Therefore, there has been provided a spring 25 which is coiled about the stem between the upper and lower 90 bearings with its upper end engaging a bearing washer 26 which bears against the lower end of the bearing 11 and its lower end engaging a bearing washer 27 which bears against the upper edges of the clamping bar 22 and yoke bar 21. With this spring 95 in place, the stem will be normally held in the lowered or operative position shown but can be readily moved upwardly against the action of the spring when so desired and either held in the raised position by hand or can be turned to the proper position to permit the teeth of the pinion 19 to press against the teeth of the rack bar 20 and thus support the stem in the raised position. It 100 will thus be seen that the stem will be slidably and rotatably mounted and further that there has been provided a lever by means of which the stem can be turned for one-half of a revolution.

This stem is to be rotated when the carriage reaches each end of its path of movement and is about to make a return movement. In order to permit the lever to be swung and turn the stem, there has been provided a bar or rod 28 which extends longitudinally of the knitting machine and at one end is provided with a supporting bracket 29 which is in the form of curved arms, the upper ones of which are connected with the bar or rod 28 and the lower ones of which are secured to the bar B by suitable fasteners. At each end, there has been provided an abutment for engagement by the lever 6 so that when the carriage approaches 110

each end of its extent of movement, the lever will be swung upon its pivot and rotary movement imparted to the stem. One of these abutments is in the form of a pin 5 or plunger 30 which is slidably mounted in ears 31 carried by the bar or strip 28 and provided with a head 32 for engagement by the lever 6. A spring 33 is positioned between the ears 31 and serve to yieldably hold the abutment pins against sliding movement but permit of sliding movement when the pin is engaged by the lever arm. Therefore, the lever arm can be swung to impart rotary movement to the stem without danger of breakage due to excess pressure being applied to the pin or turning of the stem stopped before the carriage has quite reached its full extent of movement in one direction.

20 When this attachment is in use, it is put in place upon the knitting machine with the bracket 29 secured to the bar B thus mounting the strip 28 so that it extends longitudinally of the knitting machine. The bracket 1 has its arm 2 secured to the carriage as shown and the yarn guiding device will be mounted as shown clearly in Fig. 2. The lever handle 6 extends between the abutments carried by the bar 28 and it will be readily seen that as the carriage moves, the handle will engage the heads of the plunger 30 of these abutments thus causing the lever arm to be swung upon its pivot and turn the thread carrying and guiding stem as the carriage reaches the end of its movement in either direction. The stem will thus be rotated for a half turn prior to a return movement in either direction and therefore the threads will be kept in the proper relation to each other, so that the article can be knitted with a plated yarn having the good yarn positioned outermost and showing from the outside and the cheaper yarn innermost and showing from the inner or underface of the article.

I claim:

1. A feed drive for knitting machines comprising a bearing bracket for connection with the moving carriage of a knitting machine, a stem rotatably carried by the bracket and having a thread passage, means for imparting rotary movement to the stem, and means for limiting rotation of the stem, said means consisting of a yoke bar secured to the stem and extending transversely thereof with its end portions extending to engage the bracket and limit rotation of the stem.

2. A feed guide for knitting machines comprising a bracket having upper and lower bearings, a vertical stem rotatable and slidably in the bearings and having its lower portion provided with a neck portion and a head at the lower end of the neck, the head having thread openings and the stem

above the neck being hollow to provide a thread passage, a pinion carried by said stem, a lever pivoted to the bracket and having a rack portion engaging the pinion for imparting rotary movement to the stem when the lever engages an abutment carried by a knitting machine in operative relation to the feed guide, means for limiting rotation of the stem, and means for yieldably holding the stem against upward sliding movement to move said pinion out of engagement with the rack of said lever.

3. A feed guide for knitting machines comprising a bracket having upper and lower bearings, a vertical stem rotatable and slidably in said bearings and having a thread passage, a pinion carried by said stem, a yoke arm secured to and extending transversely of said stem above the lower bearing for engaging the body of the bracket and limiting rotation of the stem, a spring about the stem between the yoke arm and upper bearing for yieldably holding the stem against upward sliding movement, a collar upon the stem beneath the pinion for engaging the upper bearing and limiting downward movement of the stem, and a lever pivoted to the bracket and having a rack portion engaging the pinion for imparting rotary movement to the stem when the lever engages an abutment carried by a knitting machine in operative relation to the feed guide.

4. A feed guide for knitting machines comprising a bracket having upper and lower bearings, a vertical stem rotatable and slidably in said bearings and having a thread passage, a pinion carried by said stem, a yoke arm secured to and extending transversely of said stem above the lower bearing for engaging the body of the bracket and limiting rotation of the stem, a spring about the stem between the yoke arm and upper bearing for yieldably holding the stem against upward sliding movement, a collar upon the stem beneath the pinion for engaging the upper bearing and limiting downward movement of the stem, and means engaging said pinion for imparting rotary movement to the stem, said means being movably carried by said bracket and moved to impart rotary movement to the stem through engagement with an abutment carried by a knitting machine.

5. A feed guide for knitting machines comprising a bracket having upper and lower bearings, a vertical stem rotatable and slidably in said bearings and having a thread passage, a pinion carried by said stem, a lever pivoted to the bracket and having a gear portion engaging the pinion for imparting rotary movement to the stem when the lever engages an abutment carried by a knitting machine, means for limiting rotation of said stem, and means for yieldably

holding the stem against upward sliding movement to move said pinion out of engagement with the rack of said lever.

6. A feed guide for knitting machines comprising a bracket having upper and lower bearings, a vertical stem rotatable and slideable in said bearings and having a thread passage, a pinion carried by said stem, means movably carried by said bracket and engaging said pinion for imparting rotary movement to the stem when engaged with operating means carried by a knitting machine, and means for yieldably holding said stem against upward sliding movement to move said pinion out of engagement with the means for imparting movement to the stem.

7. A feed guide for knitting machines comprising a bearing bracket to be mounted upon the moving carriage of a knitting machine, a thread stem rotatably carried by said bracket and permit of vertical sliding movement into and out of an operative position, means for limiting rotation of the stem, means for rotating the stem including a lever pivoted upon the bracket and having an extended free end portion, and means carried by the frame of the knitting machine for engaging the free end portion of the lever and moving the lever to impart rotary movement to the stem, means for yieldably holding the stem against upward sliding movement, and means for limiting downward sliding movement of the stem.

8. The structure of claim 7 having the means for engaging the free end of the lever comprising a bar for extending longitudinally of the knitting machine, a mounting bracket for said bar, and abutment means adjacent the ends of the bar for engagement by the lever as the carriage approaches each end of the bar when moving longitudinally of the knitting machine, each of said abutment means including a slidably mounted plunger extending longitudinally of the bar with its inner end positioned for engagement by the lever, and means to yieldably hold the plunger against sliding movement in one direction.

9. The structure of claim 7 having the means for engaging the free end of the lever comprising a bar for extending longitudinally of the knitting machine, a mounting bracket for said bar and abutment means adjacent the ends of the bar for engagement by the lever, each of said abutment means having bearing ears carried by the bar, a plunger slidably carried by the ears and extending longitudinally of the bar with its inner end positioned to engage the lever, and a spring about the plunger between the ears to yieldably hold the plunger against longitudinal movement in one direction.

In testimony whereof I have hereunto set my hand.

NAPOLEON HENRY SEYMOUR.
